UNITED STATES PATENT OFFICE.

EUGENE HANDLER, OF NEWARK, NEW JERSEY, ASSIGNOR TO GENERAL LEAD BATTERIES COMPANY, A CORPORATION OF DELAWARE.

STORAGE-BATTERY GRID.

1,293,419.

Specification of Letters Patent.

Patented Feb. 4, 1919.

Application filed May 5, 1916. Serial No. 95,534.

To all whom it may concern:

Be it known that I, EUGENE HANDLER, a citizen of the United States, and resident of Newark, in the county of Essex and State of New Jersey, have invented certain new and useful Improvements in Storage-Battery Grids, of which the following is a specification.

This invention relates to grids for storage batteries employing plates of the Faure type.

Specifically the invention relates to what are known as "double lattice grids". Such grids have two sets of bars or lattices which are held apart by ribs so that spaces for the active material are formed between. The ribs also serve to strengthen the grid. Double lattice grids as described are usually formed by casting in molds, a core or draw-bar being provided to form the spaces between the two lattices and between the ribs. When the casting has been completed it is necessary to withdraw the draw-bar. This leaves an opening at one end of the grid which should be closed to prevent dropping out of active material which has been pasted into the grid. Where the ribs extend to the extremity of the grid, the portions of the grid end between the ribs have been pushed together but the ribs have prevented the complete closure unless such a sharp bend is made about the ribs as is liable to break the grid. Also if the ribs are slotted it is difficult to press the end of the grid entirely closed and the ribs are almost certain to break at the points of bending.

I overcome the difficulties mentioned by discontinuing the ribs short of the edge of the grid left open by the withdrawal of the draw-bar, the lattices or bars extending beyond the ends of the ribs to the edge of the grid. The edges can then be pressed together so as to make a good closure and without danger of breakage of the bending parts.

In the accompanying drawing which illustrates the invention,

Figure 1 is a side elevation of a grid embodying the invention,

Fig. 2 is a fragmentary view on an enlarged scale of a portion of the grid of Fig. 1,

Fig. 3 is a section on the line 3-3 of Fig. 2, looking in the direction of the arrow, showing the separation of the lattices

beyond the end of the ribs as the grid comes from the mold,

Fig. 4 is a similar view showing the extended lattices bent into closing position,

Fig. 5 is a view similar to Fig. 2 of a modified structure having rectangular instead of diamond shaped apertures, and

Fig. 6 is a section of a plate on the line as indicated at 6-6 of Fig. 5,

Fig. 7 is a fragmentary section of the grid on the line 7-7 of Fig. 2.

Referring to the drawings and first to Figs. 1 to 4 inclusive, the grid comprises a frame 1, including the top bar 17 and the side bars 18 and 19 is substantially the thickness of the grid, from which extends the terminal projection or lug 2. Integrally joining the frame are vertical ribs as 3 separating the two lattices one of which is formed of the diagonal bars 4 crossing each other to form diamond shaped apertures as shown, while the other lattice is similarly formed of bars as 5. It will be observed that the lattices are staggered with relation to each other so that the points of intersection of the bars of one lattice are opposite the apertures of the other lattice. Beyond the ends of the ribs 3 the lattices comprise Y shaped members 6 and 6', of substantially the same thickness as the bars 85 of the lattice. The extended lattices terminate in marginal bars 7 and 8, of substantially the same thickness as the bars of the lattices. Usually the frame, lattices, bars and ribs are cast integral of antimonious 90 lead.

Fig. 3 shows clearly the extension of the lattices beyond the end 9 of a rib 3 leaving the space 10 between the portions of the lattices extending beyond. In Fig. 4 the bars 95 7 and 8 are shown pressed together closing the lower end of the grid, the lattice extensions 6 and 6' readily bending to permit this.

Referring now to Figs. 5 and 6, the structure is similar to that of Figs. 1 to 4 inclusive, except that the bars forming the lattices, that is to say the bars which cross the vertical ribs, are at right angles to these ribs instead of diagonal thereto. In the last figures one lattice is made up of the horizontal 105 bars as 13, running at right angles to the vertical ribs 14, while the other lattice is made up of the horizontal bars 15, the lattices being staggered so that a horizontal bar of one lattice is opposite the space be- 110

tween the horizontal bars of the other lattice. These lattices are separated by spaces as 16 (see Fig. 6) between the ribs.

While the invention has been illustrated in what are considered its best applications, it may have other embodiments without departing from its spirit and is not therefore limited to the structures shown in the drawings.

What I claim as new and desire to secure by Letters Patent is:—

1. An integral cast metal, substantially rectangular, storage battery grid having two lattices and separated ribs separating the lattices and dividing the space between them, and said ribs extending substantially parallel to each other and to one dimension only of the rectangle, said lattices comprising separated bars extending from said ribs and extending beyond the ends of said ribs in the direction of said dimension.

2. An integral cast metal, substantially rectangular, storage battery grid having a frame, two lattices, and separated ribs secured to said frame, said ribs separating said lattices and dividing the space between them and extending substantially parallel to each other and to one dimension only of the rectangle, said lattices comprising separated bars extending from said ribs and extending beyond the ends of said ribs in the direction of said dimension, the portions of said lattices extending beyond the ends of said ribs being pressed together.

3. An integral cast metal, substantially rectangular, storage battery grid having a

frame, two lattices, and separated ribs secured to said frame, said ribs separating said lattices and dividing the space between them and extending substantially parallel to each other and to one dimension only of the rectangle, said lattices comprising separated bars extending from said ribs and extending beyond the ends of said ribs in the direction of said dimension, each lattice having its portion which extends beyond the ends of the ribs terminating in a marginal bar.

4. An integral cast metal, substantially rectangular, storage battery grid having a frame extending partially about the grid, it being discontinued at one side thereof, a terminal or lug extending from the opposite side of said grid, vertical ribs secured to the side of said frame from which the lug extends and extending parallel to each other and to one dimension only of the rectangle, lattices secured to said ribs in separated relation, said lattices comprising separated bars extending from said ribs and extending beyond the ends of said ribs in the direction of said dimension and upon the side of the grid opposite that to which the said terminal is secured, each of said lattices having its portion which extends beyond the ends of the ribs terminating in a marginal bar at the side of the grid opposite that to which said terminal is secured.

Signed at New York in the county of New York, and State of New York, this 3rd day of May, A. D. 1916.

EUGENE HANDLER.
